UNITED STATES PATENT OFFICE.

TARGE G. MANDT, OF STOUGHTON, WISCONSIN.

HUB.

SPECIFICATION forming part of Letters Patent No. 694,292, dated February 25, 1902.

Application filed November 8, 1901. Serial No. 81,639. (No model.)

To all whom it may concern:

Be it known that I, TARGE G. MANDT, a citizen of the United States, residing at Stoughton, in the county of Dane and State of Wisconsin, have invented new and useful Improvements in Hubs, of which the following is a specification.

My invention relates to vehicle-hubs; and the object of the same is to design a hub adapted to be constructed in two sections made wholly of iron and provided with means for effectively securing the spokes therein. This object is accomplished by a simple and novel construction described and claimed in this specification and illustrated in the accompanying drawings, forming a part thereof, in which—

Figure 1 is a vertical transverse section of my hub. Fig. 2 is a section on the line $x-x$, Fig. 1, with a spindle inserted in the hub.

Like numerals of reference designate like parts in the different views of the drawings.

The numeral 1 designates the body of my hub, which has a rim 2 formed thereon. The rim 2 is traversed by a series of radially-extending spoke-sockets 3, separated from one another by V-shaped partitions 4. Spokes 5, slightly beveled on their sides at 5° , are fitted within the sockets 3.

Notches 6 are cut in the partitions 4, and in order to secure the spokes against loosening radially-extending apertures 7 are formed in the partitions 4 within the notches 6 and screws 8 inserted therein. The threads on the lower ends of the screws 8 engage the wooden spokes 5, and thereby secure them. It will be noted that the screws are placed in alternate notches and each screw serves to hold two spokes 5.

The body 1 is traversed longitudinally by a tapering bore 1°, and mounted within this

bore is a steel box 9, having shoulders 10 and 11 thereon, which respectively abut the protruding ends of the spokes 5 and the rear end of the body 1. The forward end of the box 45 9 projects beyond the body 1 at 12 and is screw-threaded. A cap 13 is fitted on the end of the box and is provided with screw-threads engaging the threads thereon. This cap 13 keeps out dust and also holds the box 9 against 50 withdrawal.

A spindle or thimble skein 14 fits within the box 9 and is held against withdrawal by a nut 15, but is free to rotate.

In practice I construct the body and rim of 55 my hub of malleable iron and the box and spindle of steel. The spokes are of wood. A new box 9 can be inserted when the old one is worn out.

I do not wish to be limited as to details of 60 construction, as these may be modified in many particulars without departing from the spirit of my invention.

Having thus described my invention, what I claim as new, and wish to secure by Letters 65 Patent, is—

The combination with a body portion bearing a rim provided with spoke-sockets, separated by V-shaped partitions having radially-extending apertures therein, of spokes 70 fitted in said sockets, screws mounted in said apertures and engaging said spokes to hold them against withdrawal, substantially as described.

In testimony whereof I have hereunto set 75 my hand in presence of two subscribing witnesses.

TARGE G. MANDT.
